UNITED STATES PATENT OFFICE.

SETH D. MCNEAL, OF JONESVILLE, MICHIGAN.

MONUMENT.

SPECIFICATION forming part of Letters Patent No. 729,391, dated May 26, 1903.

Application filed October 3, 1902. Serial No. 125,785. (No model.)

To all whom it may concern:

Be it known that I, SETH D. MCNEAL, a citizen of the United States, and a resident of Jonesville, in the county of Hillsdale and State of Michigan, have made a certain new and useful Invention in Monuments; and I declare the following to be a full, clear, and exact description of the same, such as will enable others skilled in the art to which it appertains to make and use the invention, reference being had to the accompanying drawings, and to letters of reference marked thereon, which form a part of this specification.

Figure 1 is a front view of the monument.

Fig. 2 is a side elevation of the same. Fig. 3 is a detail section of the base of the monument. Fig. 4 is a detail sectional view of the inscription-plate and adjacent parts, frame *b* being shown in position. Fig. 5 is a detail front view of the inscription-plate with edge strips in place. Fig. 6 is a detail sectional view illustrating the frame or saddle-form *b'* within recess *a*. Fig. 7 is a detail view of a raised or recessed form of letter.

The invention has relation to concrete monuments; and it consists in the novel construction and combinations of parts, as hereinafter set forth.

In building this monument certain knock-down forms are made for the base, plinth, and upper parts, these forms being varied in accordance with the design. The forms are made of board, strengthened by cleats and iron rods, which keep them from bulging when filled and tamped full of the materials of which the monument is constructed. Such a form is indicated at *a* in the drawings. The recess or saddle *a'* for receiving the tablet or inscription may also be of varied design and is provided for in the construction by placing a frame or saddle-form *b'* of suitable design within the body-form. The sections of the saddle-form are held together by screws, so that it can be taken out of the recess, when the screws are removed, piece by piece.

When the foundation for the proposed monument has been excavated and filled with stone and concrete, the form for the base of the monument is placed upon it and is filled with the materials, after which each form is placed in succession one above the other, and each form is filled as it is placed in position,

the core portion *x* of the filling being always kept a little lower than the finer material *y*, which is used as the outer portion or facing, 55 in order to prevent the coarser filling from approaching the surface, while it is nevertheless intimately united with the facing material.

The material or concrete used in making 60 the core portion of the monument is composed of Portland cement, coarse sharp sand, and boulders or pieces of broken stone of large size, not being of sufficient size, however, to come within three inches of the inner walls 65 of the forms. The facing material which encloses the core portion and is built up around it is of finer concrete, being composed of Portland cement, white sand, and crushed granite, and if a perfectly white surface is desired 70 ground marble may be added, all these ingredients being used in well-known proportions.

When raised or recessed letters are desired on the base or other portion of the monument, 75 these are provided for by means of metallic forms of letters having flanges, whereby they are attached to the inner surface of the proper form in proper position. Such a letter is indicated at *z*, Fig. 7.

In order to provide for electric wiring, as well as to strengthen the monument and rectify its vertical center, a gas-pipe or metallic tube *d* is placed in the vertical central line of the monument and the filling is built in 85 around it.

When the forms are taken away after the material has set sufficiently, the saddle-form is removed section by section, leaving the recess in condition to receive the inscription 90 plates or tablet. This tablet is designed to be made of plate glass and sheet metal, usually, in the following manner: The glass is cut to fit the recess and the matter of the inscription is etched into the rear surface thereof, after which the letters so etched may be filled in with gold or silver leaf or other suitable material, according to the desire of the purchaser of the stone. After the inscription-plate has been properly lettered a back 100 plate of colored glass is placed behind the inscription-plate, and in order to prevent the access of moisture or other matter between the two plates the marginal portions of the

plates are treated with a solution of shellac in alcohol, and the joined plates are laid upon a flat surface until they have adhered firmly to each other. Then to insure against dampness and to provide a small amount of elasticity a jacket *c* is provided, consisting of a back plate *c'*, of sheet metal, preferably zinc, which is cut to the size and shape of the plates, and edge strips *c²*, preferably of copper, are used, one for each edge, such strips being bent into channel-form to embrace and bind the glass and back plates together, lapping at their ends and being after the plates are put in position on the zinc plate soldered to said zinc plate and to each other. In this manner the tablet is formed and is made ready to be secured in the recess of the stone.

When the stone is sufficiently dried to make it safe to do so, the iron rods or bolts are removed and the forms are taken away from the faces of the monument. Then the sections of the saddle-form are removed, and the saddle portion is thoroughly moistened to facilitate the uniting of the new material of the border-shoulder to the stone. The tablet having been placed within the saddle-recess is secured in place in the following manner: An edge filling of cement or the like is plastered around the margin of the tablet, which lies with its outer face some distance within the recess *a'*, this filling adhering on one side to the edge of the tablet and the metal jacket thereof which it covers in and on the other side to the recess-wall. The frame *b* is then placed upon the filling and forced inwardly to compress the same and mold a neat and ornamental shoulder *a* around the edge of the tablet, which shoulder when set will effectually secure the tablet in position. After this portion of the material has hardened the shoulder-frame is removed. If any air-holes or inequalities should appear when the forms are removed, they can be filled and made

smooth by using the facing material, a brush being preferred for the purpose, as the finish can thereby be made very exact and fine.

In this manner it is designed to provide a strong and durable monument of any effective and tasteful design at much less cost than such a monument of block-stone. For monuments of soldiers and men whose lives were of public interest the monument will be found available, and especially so because of the ease in which inscriptions of considerable extent can be employed. The vertical tube also aids in this regard, as the monument may be varied for electric lighting.

Having described this invention, what I claim, and desire to secure by Letters Patent, is—

1. A concrete monument composed of a core portion of boulder concrete, and a facing portion of fine concrete surrounding and inclosing such core portion, and provided with a saddle-recess for an inscription-tablet, substantially as specified.

2. A concrete monument composed of a vertical metallic tube, a core portion of boulder concrete around said tube, and a facing portion of finer concrete surrounding and inclosing such core portion, and having a saddle-recess for an inscription-plate, substantially as specified.

3. A concrete monument composed of a core portion of boulder concrete, a facing portion of fine concrete surrounding and inclosing such core portion, a recess in such facing portion, an inscription-tablet in such recess and a shoulder of concrete engaging said tablet, substantially as specified.

In testimony whereof I affix my signature in presence of two witnesses.

SETH D. MCNEAL.
